UNITED STATES PATENT OFFICE.

CHARLES F. IMM, OF DETROIT, MICHIGAN.

FOLDING BED.

1,264,301.

Specification of Letters Patent. Patented Apr. 30, 1918.

Application filed December 29, 1917. Serial No. 209,451.

To all whom it may concern:

Be it known that I, CHARLES F. IMM, a citizen of the United States of America, residing at Detroit, in the county of Wayne 5 and State of Michigan, have invented certain new and useful Improvements in Folding Beds, of which the following is a specification, reference being had therein to the accompanying drawings.

10 This invention relates to a folding bed, and has special reference to a piece of furniture as a bench, settee, or oblong seating structure that may be easily and quickly converted into a couch or single or double bed.

15 The primary object of my invention is to provide an oblong seating structure in which may be practically housed or concealed frames and supports, which when in extended positions will coöperate with the 20 structure in providing a bedframe that may be safely used.

A further object of my invention is to provide a convertible piece of furniture of the above character that is susceptible to any desired upholstery finish, and wherein the 25 parts are constructed with a view of being easily assembled and readily manipulated.

Reference will now be had to the drawings, wherein—

30 Figure 1 is a plan of a portion of the piece of furniture showing parts thereof extended to provide a bed structure;

Fig. 2 is a longitudinal sectional view of the same;

35 Fig. 3 is a cross sectional view of the piece of furniture with parts thereof folded;

Fig. 4 is a longitudinal sectional view of a portion of the piece of furniture taken on the line IV—IV of Fig. 3;

40 Fig. 5 is a view similar to Fig. 3 showing parts of the piece of furniture as being swung to open or extended positions;

Fig. 6 is a perspective view of a modified form of hinge;

45 Fig. 7 is a perspective view of the framework of a piece of furniture, showing parts thereof extended to provide a bed frame, and

Fig. 8 is a perspective view of a settee or 50 sofa as an example of a piece of furniture that may embody my invention.

To put my invention into practice, I provide a boxlike structure which includes a bottom frame 1, end frames 2, a rear wall 3, 55 a bottom wall or panel 4 of the frame 1,

and a front wall 5, said front wall being approximately half the depth of the end frames 2 or the rear wall 3, with the upper edge thereof beveled, as at 6.

Mounted in the confronting faces of the 60 end frames 2 adjacent the upper and front edges thereof, are inwardly projecting hinged pintles 7 and these pintles are provided with strapped hinges 8. Connected to said hinges is an inner frame 9 and an 65 intermediate frame 10. The inner frame 9, when in an inactive position, rests upon stops 11 carried by the end frames 2, and when said inner frame is in active position, said frame engages a bar 12 connecting the 70 end frames 2 at the upper edge of the rear wall 3. The inner frame 9 has the side arms thereof recessed or cut away, as at 13, to provide clearance for legs 14 forming part of an outer frame 15 hinged connected to 75 the intermediate frame 10, as at 16.

The inner frame 9 has a pivoted head piece 17 movable with said inner frame and normally supported thereby, but said pivoted head piece may be raised so that easy 80 access may be had to the lower part or contents of the boxlike structure.

The confronting hinged ends of the inner and intermediate frames 9 and 10 are beveled, as at 18, so that the intermediate frame 85 10 may contact with the inner frame 9 and cause said inner frame to be elevated into a plane with the intermediate frame 10, when said intermediate frame is extended.

Pivots connected to the hinged end of 90 the intermediate frame 10, by straps 19, is an auxiliary front wall 20 having the lower edge thereof beveled so as to rest upon the upper edge of the front wall 5 and complete the front wall of the boxlike structure, 95 when the intermediate and outer frames 10 and 15 are folded therein. The auxiliary wall 20 is automatically brought into position on the front wall 5 and to prevent outward displacement of the auxiliary front 100 wall 20 relatively to the fixed front wall 5, the upper edge of the wall 5 has a strip 21. The side arms of the intermediate frame 10 are provided with outwardly projecting studs 22 and these studs are adapted to be 105 engaged by pivoted gravity links 23 carried by the outer frame 15 such engagement taking place when the outer frame is folded on to the intermediate frame, and then said frames are held together so that they may be 110

bodily swung into the boxlike structure, with the legs 14 of the outer frame 15 extending downwardly in the recesses or cut away portions 13 of the inner frame.

5 The intermediate frame 10 has the side arms thereof provided with lateral flanges 24, and as best shown in Fig. 4, these lateral flanges are adapted to overlie the upper ends of the end frames 2 when the intermediate frame 10 is folded, thus supporting the intermediate frame in the boxlike structure.

10 On the free edge of the outer frame 15, there is a hinged extension 23 and this hinged extension is adapted to coöperate with the frames 9, 10 and 15 in supporting a spring, mattress, cushion or other yieldable body, which may be detachable relatively to the frames in order that it may be folded and 15 placed in the lower part of the box structure. The frames 9, 10 and 15, particularly the frame 15, are susceptible to any desired upholstery and this is particularly true of the boxlike structure so that the entire structure will represent a piece of furniture, for 20 instance as shown in Fig. 8.

25 In order that the frames 10 and 15 may be compactly assembled within the boxlike structure, it is preferable that the upper edges of the side arms of the frame 9 be beveled or tapered to receive similarly shaped side arms of the frame 15, as best shown in Fig. 3, where it will be observed that the frame 15 rests upon the frame 9, 30 while the frame 10 is supported by the lat-

eral flanges 24 engaging on the end frames of the boxlike structure.

35 In Fig. 6, a modified form of hinge 26 is shown that may be used in lieu of the strap hinges 8, and while in the drawings there are illustrated the preferred embodiments of my invention, it is to be understood that the structural elements are susceptible to such variations and modifications as fall within the scope of the appended claim. 45

What I claim is:—

A piece of furniture comprising a boxlike structure having a front wall of less depth than said structure, hingedly connected inner and intermediate frames carried by said boxlike structure above the front wall thereof with said inner frame normally in said boxlike structure and said intermediate frame adapted to be swung therein to form the top of said boxlike structure, an auxiliary front wall carried by the intermediate frame and adapted to be raised on to the front wall of said boxlike structure to complete said wall, an outer frame connected to said intermediate frame and adapted to be 50 folded thereon to occupy a position between said inner and intermediate frames in said boxlike structure, and legs carried by said outer frame.

55 In testimony whereof I affix my signature 60 in the presence of two witnesses.

CHARLES F. IMM.
